UNITED STATES PATENT OFFICE.

SIMON COOPER, OF BROOKLYN, NEW YORK.

LABELING MACHINE.

Application filed December 12, 1918. Serial No. 266,375.

To all whom it may concern:

Be it known that I, SIMON COOPER, a citizen of the United States, residing at Brooklyn, in the county of Kings and State 5 of New York, have invented certain new and useful Improvements in Labeling Machines, of which the following is a specification.

The subject of the present invention is a 10 machine for applying labels or "stickers" to articles in the nature of packages of soap.

The objects of the invention have been to provide practical and relatively simple 15 mechanism for automatically and expeditiously applying the labels and securing them firmly in place. Special objects have been to provide for the application of labels to the opposite ends of each package.

20 According to my invention the articles are fed in a row through the machine and the consecutive articles are automatically registered at a label-applying station where the labels are withdrawn from their magazines and after being "gummed" are pressed into firm engagement with the registered articles.

25 The means by which these several actions are accomplished and the various details of 30 the invention will appear as the specification proceeds.

The accompanying drawings illustrate a practical embodiment of the invention, but I would have it understood that the form 35 may vary without departure from the true spirit and scope of the invention, as defined in the appended claims.

In said drawings, Figure 1 is a side elevation of the machine as designed for applying 40 labels to the opposite ends of soap packets; Figure 2 is an enlarged cross-sectional view thereof, taken substantially on the plane of line 2—2 of Figure 1, showing particularly the presser mechanism; Figure 3 is a side and partly sectional view, 45 showing particularly the adhesive applying mechanism; Figure 4 is a cross-sectional view of the conveyor mechanism, taken substantially on the plane of line 4—4 of Figure 3; Figure 5 is a similar view of the adhesive applying mechanism taken substantially on line 5—5 of Figure 1; Figure 6 is a detail partly sectional view of the 50 registering mechanism; Figure 7 is a detail view of the label magazines and transfer

pads; Figure 8 is an illustration of the transfer pads in another position; Figure 9 is a detail view of the carrier pad and transfer fingers for the oblong label; and Figure 10 is a similar view of the carrier 60 pad and transfer fingers for the round label; Figures 11 and 12 are detail views of the label applying fingers in successive positions; Figures 13 and 14 are top plan and end views and the carriage mechanism of 65 the transfer fingers; Figures 15 and 16 are side and end views of the feeding-in conveyor mechanism; Figure 17 is a cross-sectional view of the same taken substantially on line 17 of Figure 15; Figure 18 is a plan 70 view of the discharge mechanism, showing the side pressing belts but omitting the top and bottom conveyor belts; Figure 19 is a perspective view of one of the labeled 75 packets.

Referring now to the drawings more in detail: 1 designates the base of the machine, supporting at one end uprights 2 and end extensions 3 which, with the uprights 9 and 12, form a frame supporting the package 80 trough 4. This frame also serves as a mounting for the conveyor tapes. There are four of these at this, the feeding-in end of the machine, a pair of lower tapes or endless belts 15 having their upper runs traversing the bottom of the trough (see particularly Figures 1, 15, 16 and 17) and a pair of upper tapes 10, disposed above the lower tapes, with their lower runs about on a level with the top of the trough, the spacing of the upper and lower sets of tapes being such as to insure a proper gripping and feeding engagement with the packages, which in this case are the wrapped packages 175 of soap. The upper tapes are 85 shown supported at one end on pulleys 7, mounted on shaft 5, which is journaled in bearings 6 and at the opposite end on pulleys 8, carried by a shaft journaled in the frame uprights 9. In similar fashion the 90 lower tapes are supported on pulleys 13, carried by shaft 14 and on pulleys 16, belt-tightening rolls 11 and 17 being provided for maintaining the upper and lower sets of belts at the proper tension. 105

The upper and lower pulley shafts 5 and 14 are geared to rotate in unison by a train of inter-meshing gears 18, 19, 20 and 21 and an intermittent feeding movement is imparted thereto by means of a ratchet 22, 110

fast on shaft 14, engaged by a pawl 23 mounted on bell crank lever 24. This pawl-carrying lever is mounted to rock on the shaft 14, and is operated by means of a 5 link 25 connected with a pin 26, carried by crank 27, on the shaft 28. Shaft 28 is driven by miter gears 29, 30 from shaft 31, as more clearly appears in Figures 3 and 4.

Rising from the base 1, are the yoke 10 frames 32, which support the label magazines 33 and 34, the first being designed to hold a stack of round labels 173, and the other to hold oblong labels 174, such as shown in Figures 7, 8, 9, 10 and 19.

15 The label transfer mechanism includes rock shafts 35 and 36 journaled in the up-standing frame 32 and connected to operate in unison by intermeshing gears 37, shaft 36 having an actuating arm 38 engaged by 20 link 39, carrying a roll 41 bearing on cam 40 on shaft 31. Rock shaft 35 carries a rock arm 42 terminating in an enlargement or pad of approximately the size of the round labels, said pad having recesses or slots 43 25 therein to accommodate the label transfer fingers. Similarly the rock shaft 36 carries a rock arm 44 terminating in a pad 45 of approximately the shape of the long labels and having cut-outs 46 therein for 30 the long-label transfer fingers. The transfer pads are, by the mechanism described, swung from a position engaging the bottom labels in the magazines (Figure 7) to the upright positions shown in Figure 8, the 35 shape of the cam being such as to permit the pads to rest or dwell in this latter position.

The transfer fingers are operated by the following mechanism: Slidably mounted on 40 a guide 47 (Figures 3, 4, 13 and 14) is a carriage 48, which is reciprocated by a link 49 and a rock lever 50, pivoted at 51 and carrying a roll 50', engaged in the cam 52, on shaft 31. On opposite sides of carriage 45 48 are studs 53 and 54. Stud 53 serves as a support for a rock lever 55 having a rear-ward extension 56, carrying a stop pin 57 and a forwardly extending arm 58 carrying a relatively fixed gripping jaw 59, with 50 which cooperates a relatively movable jaw 61. This movable jaw is mounted on the upper end of a stud 60, pivoted on rock lever 55 and is normally held closed against the other jaw by a spring 63, connected be- 55 tween an angular arm 62 of said movable jaw and an anchorage 64 on the rock lever. On the lower end of the pivot stud 60, is a rock arm 65, carrying a pin 66 for engage- 60 ment with operating mechanism to be described. This constitutes the gripper mechanism for the smaller round labels.

The gripper mechanism for the oblong labels is of generally similar construction, embodying a rock lever 67, pivoted on stud 65 54, having a rearward extension carrying

stop pin 68, and forward extensions 69 forming anchorages for springs 70, which are connected with the angularly outstanding arms 71 of the pivoted jaws 71', which latter are mounted on the upright stud 72 and are 70 thus held normally closed against the relatively fixed jaws 73. The jaws 71' are opened by means of a lever 74 outstanding from the jaw pivot stud 72 and carrying pins 75 disposed in front of the angular 75 arms 71 of the jaws. On the lower end of the pivot stud 72 is a rocker arm 76 carrying an abutment pin 77.

The jaw carrying levers 58 and 67 are forced outwardly by the springs 78 and 79, 80 housed in the carriage, the outward movement of such levers being governed by engagement of the stop pins 57 and 68 with the sides of the carriage. During the outward stroke of the carriage the grippers are 85 forced inwardly or toward each other by the engagement of the rollers 80 and 83 on the gripper levers 58 and 67, with the inclined cam tracks 81 and 84 on the sections 82, 85 of the frame. 90

Journalled in the frame, beneath the carriage, are a pair of rock shafts 86 and 89 connected together by gears 90 and 190 and operated by a rock arm 87, engaging with cam 188 on shaft 31 (see Figures 2, 3 and 14). Rock shaft 86 carries an upstanding bar 88 operating as a lever for engagement with pin 77 to rock the gripper stud 72 to open gripper jaws 71' and shaft 89 carries a corresponding arm 91, engaging pin 66 100 to open gripper jaw 61.

The label applying mechanism will now be described. This mechanism, as is more clearly shown in Figures 2, 11 and 12, comprises a pair of opposed slides 92 and 98 105 working in guideways in framing 82, 85 and operated from a cam 102 on the main shaft 31, through the medium of a double ended lever 96, pivoted at 97 and carrying a roll 101 engaging in the cam groove 100, 110 one end of said lever being connected by link 95, rock lever 94 and link 94', with slide 92 and the other end of lever 96 being connected by link 99 with slide 98. The slide 92 carries a presser 103 in the nature 115 of a bell crank lever pivoted at 105, having one arm provided with a presser pad 104 to engage the upper side of the package. Also mounted in this slide is a plunger 106, nor-mally pressed inward by a spring 108, said 120 plunger carrying on its inner end a pad 107, for engaging the adjacent end portion of the package.

The slide 98 carries a pair of pressers 109 and 110, also in the nature of bell crank 125 levers mounted at the inner end of the slide and adapted to engage over the top and bottom of the package. The angular arms 110^a of these pressers are operated on by ex-pansion springs 110^b seated in recesses in 130

- the end of the slide and operating to normally hold these pressers spread open in the nature of jaws (see Figure 11). Slidably mounted in the sliding carriage 98, is a 5 plunger 111, normally pressed inwardly or extended beyond the inner end of the carriage by a retractile spring 112^b, said plunger carrying a pad 112^a for pressing engagement with the end portion of the package.
- 10 The packages are registered with respect to the several mechanisms described by means of a stop 112, in the nature of a wedge-shaped lug, carried by the horizontal arm of a bell crank lever (Figures 1 and 6) 15 pivoted at 113 and carrying a pin or roll 114 on its lower dependent arm, engaging with a cam track in the cam 115 on main shaft 31.
- The feeding-out mechanism is made up of 20 the following instrumentalities—see Figures 1 and 18: Running in opposite sides in the delivery end of trough 4 are the vertically disposed belts 116, 119, the same being carried by pulleys such as indicated at 116^a, 117.
- 25 The pulleys 117, at the outer ends of these belts carry spiral gears 118, meshing with corresponding gears 120 on shaft 121, said shaft carrying also a spur gear in mesh with the idler 122, which meshes with gear 123, 30 the latter meshing with a gear on the shaft 125. Upper and lower delivery tapes are also provided, similar to the upper and lower tapes at the feeding in end of the machine. The upper pair of tapes 127 are supported 35 on pulleys 126 located over the inner end of the delivery portion of the trough and pulleys 129 mounted on shaft 121 and similarly the lower set of tapes 130, which travel over the bottom of the trough, are carried at their 40 inner ends on pulleys 131, and at their outer ends on pulleys 132, mounted on shaft 125. These upper and lower belts or tapes are held properly tensioned by belt tighteners 128, 131'. An intermittent feed is imparted 45 to both the side and the top and bottom belts by a ratchet 133 on the lower belt shaft 125, engaged by a pawl 134, which is operated by a link 135, connected with crank 136 on the cross shaft 137, which is driven by 50 miter gears 137' from shaft 31, the action being substantially similar to the intermittent feeding action of the feeding-in belts.
- We take up now the adhesive applying mechanism—Figures 1, 2, 3, 5: The framing members 82, 85 carry upright guides 138, 139, for a vertically sliding frame 140, carrying pivot studs 141, 142 for the arms 143, carrying the ductor rolls 144. These ductor carrying arms are forced toward each 55 other by springs 145, the extent of such movement being limited by the adjustable stop screws 146. The ductor frame 140 is reciprocated by an arm 148 projecting from sleeve 149 on shaft 150, said arm having a 60 forked or s'otted end 150' engaged with a pin 147 on the frame and provided with an actuating arm 151, carrying a roll 152, engaging cam 153 on the shaft 31.
- The glue box or adhesive container is designated 154. Within said box are mounted 70 the glue rolls 155, on shafts 166, said shafts carrying on their outer ends gears 167 connected by the gears 168. These glue rolls are driven continuously by a gear 169 on shaft 31 in mesh with the adjacent gear 75 167. The thickness of the layers of glue taken up by the rollers 155 is regulated by the scraper slides 170 which may be adjusted by the thumb screws 173.
- Power may be applied to the machine 80 through the medium of a pulley on shaft 150', which, as shown in Figure 2, is provided with a pinion 171 in mesh with a gear 172, on the main shaft 31.
- Operation: The packages to be labeled are 85 fed, side by side, into the entrance end of the conveyor trough at the right hand end of the machine, Figure 1, and the row of packages is advanced intermittently, the width of a package at a time, by the pawl and 90 ratchet feed 23—22 of conveyor tapes 10, 15, the line being arrested each time, with successive packages in position to be labeled, by the register stop 112 (Figures 1 and 6). As the transfer pads swing downwardly in- 95 to an upright position, Figure 5, the ductor rolls 144 are elevated, through the action of cam 153, contacting as they rise, with the outward faces of the pads and depositing a film of adhesive thereon. As the ductor rolls 100 drop back, the cam 40 and connections therefrom, swing the transfer pads first upward (Figure 7) into contact with the bottom labels in the magazines and then back again to the upright position, said pads, as they 105 are retracted, carrying with them the bottom labels 173, 174, by reason of the adhesion of the labels to the adhesive faces of the pads. At the end of this last movement the labels 110 are in position to be taken by the grippers 73—71' and 59—62 (Figures 9, 10, 13) on carriage 48, which advances at the proper moment, through the action of cam 52. The grippers are opened as they advance, through the medium of the rocker cams 88, 91 (Figures 2 and 14), which, after the grippers 115 have passed on into the notches 43, 46, provided for them in the pads, rock back to permit the grippers to close on the two labels. The gripper carriage now returns to its first 120 position and in such movement the engagement of the gripper rollers 80, 83 with the relatively stationary cam tracks 81, 84 (Figure 13) forces the grippers with their labels, toward the package in the feed chute. At 125 the end of this carriage movement the rocker cams again open the grippers and at this time the slides 92, 98 have been shifted inward or toward each other by the cam 102 (Figures 11 and 12), far enough for the 130

plungers 107 and 112^a to engage the labels 173 and 174 and carry them into engagement with the ends of the package. In the continued inward movement of the slides the side pressure pads 104 and 109, 110 are rocked to fold the labels over the top and around the top and bottom of the package, as shown, in Figure 12, the rocking of such pads being accomplished by the engagement of the angular arms 104^a and 110^a, with the plunger heads 107, 112^a, in back of which said arms are disposed. In this way the labels are first stuck to the ends of the package by the spring pressed plungers and are then folded over the top and bottom of the package, being pressed thereby into firm engagement with the package at all points of contact. In the case illustrated, the round label 173 only covers a part of the end and is lapped over the top of the package (Figure 19) and the oblong label 174 extends across the end and laps over both the top and bottom of the package.

The presser slides after thus sticking the labels on the package, are retracted to free the package and permit it to feed forward on the next feeding movement of the feed belts 10, 15. At the moment of feeding forward, the register stop 112 is retracted out 25 of the path of the packages but just about at the end of such feeding movement the stop rises, the wedge point of the stop (Figure 6) interposing itself between adjoining packages, forcing the one package forward and catching and holding the other package to stop the next package to be operated on, in proper register with the labeling devices.

As the line of packages is advanced the 40 labeled packages pass on into the grip of the feeding out belts at the left hand end of the machine, Figure 1, and these feed the labeled packages on out of the way for incoming packages, applying pressure at the same time to the ends and tops and bottoms 45 of the packages, holding the labels to the packages and preventing them from curling away from the packages or coming loosened while they are drying and setting.

The operation of this machine is thus 50 entirely automatic, it being necessary only to provide a proper supply of the packages and to keep the label magazines properly charged and the glue box supplied with adhesive. The labels furthermore are accurately positioned and firmly secured in place. The machine may be speeded to operate at a rapid rate, this being possible by reason of the facts that all the movements 60 are relatively simple and the action is entirely automatic. Gumming up of the parts is prevented by reason of the fact that the transfer grippers engage with small un-gummed areas of the labels overlying the notches in the transfer pads, said labels re-

ceiving no adhesive at such points by reason of the breaks in the adhesive receiving surface at these points. The presser pads in bending the labels around the corners of the package, slide over the surface of the 70 labels, smoothing out any creases and fitting the label closely to the package, which may be more or less loosely wrapped and somewhat irregular in shape. The guide trough 75 provides a substantially continuous path through the machine for the articles, it having a suitable break or interruption therin at the label applying station, substantially as indicated at 175' in Figure 6, to enable the label applying devices to operate 80 on the package registered by the stop device 112.

I claim:

1. A labeling machine comprising a label magazine, a label pad, means for applying adhesive to said pad, means for operating said pad to engage the same with a label and extract the label from the magazine, a swinging gripper operating in a plane to one side of the path of movement of the articles 90 for removing the label from the pad and transporting the same out registry with the article, and means for pressing said label on an article.

2. In a labeling machine, a label magazine, 95 a transfer pad of the approximate outline of the labels and provided with a recessed portion in the face thereof, means for applying adhesive to the face of the pad, means for engaging the adhesive-coated face of 100 the pad with a label in the magazine and for retracting the pad to thereby withdraw said label and a gripper swinging in a plane to one side of the path of movement of the articles for removing the label from the 105 pad and transporting the same into registry with the article, said gripper operating in the recess in the face of the transfer pad.

3. In a combination like that set forth in claim 2, for a carriage mounting the gripper 110 and means for operating said carriage.

4. In a combination like that set forth in claim 3, a presser and means for operating the same to press the label on an article.

5. In a labeling machine, a label magazine, 115 a transfer pad provided with a recess in the face thereof, a reciprocatory adhesive applying member operating over the face of said pad, means for engaging the adhesive-coated face of the pad with a label and a 120 swinging gripper for conveying the label from the pad, said gripper operating in the recess in the pad to engage the ungummed area of the label overlying said recess.

6. In a labeling machine, a pair of swing- 125 ing transfer pads, label magazines, means for swinging the transfer pads toward and away from said magazines, ductor rolls, an adhesive container, distributing rolls working in said adhesive container, means for 130

carrying the ductor rolls from engagement with said distributor rolls into engagement with the transfer pads while in their retracted position, reciprocating pressers, an article conveyor passage between said pressers and grippers for stripping the labels from the transfer pads and positioning them to be operated on by said pressers.

7. In combination, article conveying means, reciprocating members at opposite sides of said conveying means, vertically movable presser pads on said members disposed to engage the tops and bottoms of the articles in said conveying means, and yielding plungers disposed in line with the ends of the packages and projecting beyond the presser pads to operate on the ends of the articles in advance of the engagement of the presser pads with the articles.

20 8. In combination, article conveying means, reciprocating members at opposite sides of said conveying means, presser pads on said members disposed to engage the tops and bottoms of the articles in said conveying means, yielding plungers disposed in line with the ends of the packages and projecting beyond the presser pads to operate on the ends of the articles in advance of the engagement of the presser pads with the articles, said presser pads being pivotally supported and having angular arms engaging the plungers to rock said pads into clamping engagement with the articles.

35 9. In a labeling machine, opposed slides, outstanding presser pads on the opposed ends of said slides, plungers mounted in said slides, springs for projecting said plungers beyond the presser pads and means for closing the presser pads on an article interposed between the slides, after the spring pressed plungers have engaged the same.

40 10. A reciprocating presser slide, a spring pressed plunger mounted therein and a rocking presser pad mounted on the slide and provided with an angular operating arm disposed rearwardly of and adapted to be operatively engaged by the plunger in the yielding movement thereof.

45 11. In combination with an article conveying means, a carriage reciprocating longitudinally thereof, grippers carried by said carriage at opposite sides of the article conveying means, means for opening the grippers substantially at the end of travel in each direction, and means for forcing the grippers toward the article conveying means substantially at the end of travel in one direction.

50 12. In combination with an article conveying means, a carriage reciprocating longitudinally thereof, grippers carried by said carriage at opposite sides of the article conveying means, means for opening the grippers substantially at the end of travel in each direction, means for supporting labels

in position to be taken by said grippers substantially at the end of travel in one direction and label applying devices for operating on said labels substantially at the end of travel in the opposite direction.

70

13. In combination with an article conveying means, a carriage reciprocating longitudinally thereof, grippers carried by said carriage at opposite sides of the article conveying means, means for opening the grippers substantially at the end of travel in each direction, label magazines at opposite sides of the article conveying means near one end of the carriage travel, transfer pads for withdrawing labels therefrom and supporting them in the bite of the opened grippers and pressers at opposite sides of the article conveying means near the opposite end of the carriage travel.

75

14. In combination with an article conveying means, a reciprocating gripper, means for opening said gripper substantially at the end of its travel in opposite directions, means for supporting labels in the bite of said gripper substantially at the end of its stroke in one direction and a presser for operating on the label substantially at the other end of the gripper travel.

80

15. In combination with an article conveying means, a reciprocating gripper, means for opening said gripper substantially at the end of its travel in opposite directions, means for supporting labels in the bite of said gripper substantially at the end of its stroke in one direction, a presser for operating on the label substantially at the other end of the gripper travel, and means for shifting the gripper toward the article conveying means at said latter point of travel.

85

16. In combination with label applying mechanism, intermittently operating conveyor mechanism engaging the tops and bottoms of the articles to intermittently advance articles thereto, means for registering the articles at the label applying station and delivery means engageable with the ends, tops and bottoms of the articles for withdrawing the labeled articles from in front of the articles being advanced to the label applying mechanism.

90

17. In combination with label applying mechanism, a feed trough for guiding articles to and away therefrom, feeding-in belts operating on articles in said trough to advance the same to said label applying mechanism and delivery belts engaging the labeled sides, tops and bottoms of the articles for delivering the articles and for holding the labels engaged with such articles during such delivery movement.

100

18. In a labeling machine, an article conveyor, label affixing means adjacent said conveyor, means for intermittently advancing a row of articles on said conveyor, a registering stop and means for interposing said stop

120

125

130

into the advancing row between adjacent articles to separate the same and stop the articles at the label affixing means.

19. In a labeling machine, an article conveyor, label affixing means adjacent said conveyor, means for advancing a row of articles on said conveyor, a registering stop, means for interposing said stop into the advancing row between adjacent articles to separate the same and stop the articles at the label affixing means, said stop having a wedging point to facilitate its entrance between the adjacent articles.

20. In combination with an article trough, label affixing means adjacent the trough, means for intermittently advancing the articles in said trough, a register stop and means for intermittently projecting said stop between adjacent advancing articles in said trough approximately at the end of each feeding movement.

21. In combination with an article trough, label affixing means adjacent the trough, means for intermittently advancing the articles in said trough, a pivoted bell crank having a stop lug on one arm for interposition in the article trough between adjacent advancing articles and a cam operatively engaging the other arm to intermittently rock the bell crank.

22. In a labeling machine, feeding-in belts engaging the tops and bottoms of the articles, means for applying labels to the ends and top and bottom portions of the articles and delivery belts engaging the ends and the tops and bottoms of the labels.

23. In a labeling machine, horizontally reciprocating opposed label pressers, vertically reciprocating ductor rolls, swinging transfer pads arranged to be engaged by said ductor rolls and grippers for shifting the labels from said transfer pads to the reciprocating pressers.

24. In combination, an article conveyor, grippers reciprocating longitudinally thereof, label magazines at opposite sides of the article conveyor, transfer pads swinging from said magazines to a vertical position at opposite sides of the article conveyor, rising and falling ductor rolls for applying adhesive to the transfer pads when the same are vertically disposed, reciprocating pressers at opposite sides of the article conveyor and means for opening the grippers when in the course of the reciprocation thereof said grippers are adjacent the transfer pads and the pressers.

25. In a machine to apply labels to a wrapped package the combination of label affixing means, means for intermittently feeding the packages to said label affixing means, a register stop, and means for operating said register stop to break into the line of moving packages approximately at the end of each feeding movement.

26. In a machine to apply labels to a wrapped package, the combination of label affixing means for feeding the packages intermittently against a register stop which breaks into the line of moving packages, and other means for feeding the packages out of the machine and for applying pressure to the freshly labeled packages.

27. In a machine for labeling packages, the combination of a label affixer, a stop to register packages in a labeling position, adhesive transfer pads and transfer means for taking the labels from the adhesive pads and presenting the same to the label affixer.

28. In a machine for labeling packages, the combination of a stop to register a package in a labeling position, a label magazine, glued pads for extracting the labels from the magazine, and transfer means for taking the labels from the glued pads and transporting them into registry with a package in labeling position, and means for applying the labels to the packages.

29. In a machine for labeling packages, the combination of a stop to register a package in a labeling position, a label magazine, glued pads for extracting the labels from the magazine, and transfer means for taking the labels from the glued pads and transporting them into registry with a package in labeling position, means for applying the labels to the packages, such means including folders to fold the label around the corners of the packages.

30. In a machine for labeling packages, gluing devices for holding the labels, label transfer means moving in a plane to one side of the path of movement of the packages for removing the labels from the gluing device and supporting them in the path of movement of the packages and means for operating said transfer means to carry the labels close to the packages, said transfer means carrying a clamp which grips but a small portion of the label.

31. In a machine for applying labels to a loosely wrapped package whose faces are not perfectly square, a combination of transfer means to bring freshly gummed labels in contact with the packages, a reciprocating carriage and resilient presser pads associated with said carriage and shaped to conform said gummed labels with the surface of the packages upon reciprocatory movements of said carriage.

32. In a machine for applying labels to a loosely wrapped package whose faces are not perfectly square, a combination of transfer means to bring freshly gummed labels in contact with the packages, a reciprocating carriage and resilient presser pads associated with said carriage and shaped to conform said gummed labels with the surface of the packages, when brought into contact therewith upon reciprocatory movement of said carriage.

carriage, said transfer means arranged to hold only one portion of the label and the presser pad being arranged to slide over the balance of the surface of the label to smooth out creases.

33. In a machine for applying freshly gummed labels to a package, a combination of feed belts, a register stop to locate the packages to be labeled, transfer pads, means for applying adhesive to parts only of said pads, a label magazine, means for operating the pad to remove the labels from the maga-

zine by means of the adhesive applied to the surface thereof, a removing clamp operating in a plane clear of the package for engaging the ungummed portions of the labels, means for operating said clamp to carry the labels into registry with the packages and composite means for detaching the labels from the transfer arms and for fastening the labels to the packages around the edges thereof.

In testimony whereof I affix my signature.
SIMON COOPER.
